CLAIM

The ornamental design of a retractable golf utility device, as shown and described.

DESCRIPTION

FIG. 1 is a perspective view of the article of this invention;
FIG. 2 is a front elevational view of the article of this invention;

FIG. 3 is a back elevational view of the article of this
invention;

FIG. 4 is a top view of the article of this invention;

FIG. 5 is a bottom view of the article of this invention;

FIG. 6 is a right side elevational view of the article of this invention; and,

FIG. 7 is a left side elevational view of the article of this invention.
